H. M. STURGIS

MOP HEAD

Filed Nov. 14, 1924

UNITED STATES PATENT OFFICE.

HERBERT M. STURGIS, OF KANSAS CITY, MISSOURI.

MOP HEAD.

Application filed November 14, 1924. Serial No. 749,814.

To all whom it may concern:

Be it known that I, HERBERT M. STURGIS, a citizen of the United States, residing at Kansas City, in the county of Jackson and State of Missouri, have invented certain new and useful Improvements in Mop Heads; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to mop heads and the primary object of the invention is to provide an inexpensive easily constructed reversible mop head whereby the mop fabric may be reversed so that both sides can be used. The device is shown in combination with a mop fabric in the form of an envelope which fits over the head and which may be removably secured thereto in a convenient manner.

The details of construction illustrating the generic embodiment of my invention will be specifically described hereinafter, reference being had to the accompanying drawings, in which

Fig. 1 is a perspective view of a mop head constructed in accordance with my invention.

Fig. 2 is a detailed perspective view of the ferrule for securing the handle of the mop to the shank of the head.

Fig. 3 is a sectional view through the shank and the ferrule in co-operative relation.

Fig. 4 is a detailed perspective view of one of the shank elements, and

Fig. 5 is a perspective view of the completed mop, part of the handle being broken away.

The mop head is shown as comprising a substantially pentagonal flat member or frame made of one piece of wire. The single strand of wire is bent midway its ends at 1 to form two diverging end bars or arms 2 and 3 terminating in longitudinally disposed parallel side bars 4 and 5 bent transversely to form end bars or arms 6 and 7, then bent to form diverging inwardly turned arms 8 and 9 with a space 10 between them and between the arms 6 and 7 so that the shank to be hereinafter described may swing in an unobstructed manner. The di-

verging longitudinal arms 8 and 9 are bent at their inner ends to form transverse members 11 and 12 terminating at the longitudinal center of the frame, the members 8 and 9 being then bent back upon themselves to form braces 13 and 14 which may be spot welded at 15 and 16 to the arms 4 and 5, thus a substantially pentagonal skeleton frame is provided to be received by the mop fabric.

The members 11, 12, 13 and 14 combine to constitute brackets to receive a sheet metal clip 17 formed by bending a piece of sheet metal over upon itself and crimping it at the end edges of the sheet as indicated at 18, the intermediate portion of the sheet being formed with a tubular portion or bearing 19 to receive the outstanding ends 20 and 21 of a wire shank which is bent intermediate its ends to form a loop 22, the shank intermediate portions 23 and 24 lying close together with the ends 20 and 21 in the bearing 19 so that the shank is hinged to the clip within the perimeter of the frame.

There is a cap piece 25 fitted over the loop and having a shoulder 26 at the intersection of the convex end 27 and the enlarged threaded portion 28, the shank being provided with an opening 29, the purpose of which will be presently explained. The lower edge of the cap piece is bent under to form a groove 30 to receive the upper edge 31 of a cone 32 having a lower restricted end fitting around the members 23 and 24. The ferrule is shown as consisting of two pieces. The sleeve 33 has prongs 34 imbedded in the handle 35. The opposite end of the member 33 is provided with a shoulder 36 with an edge bent under as at 37 to receive the in-turned flange 38 of the member 39 of the ferrule.

The member 39 is provided with a collar 40 to act as a stop for the threaded collar or ring nut 41 which has an inturned flange 42. The threaded portion 43 of the collar 41 engages the threaded member 28. The ferrule member 39 has prongs 44 which are adapted to engage the openings 29 when the handle is applied. In this manner the prongs 44 can be easily inserted in the openings 29 and since the collar 41 has free play on the ferrule member 39, it will be apparent that the collar can be quickly screwed on the threaded member 28 to make a quick tight connection and liability of the collar unscrewing will be eliminated because there

can be no relative turning movement of either the ferrule or the shank head to loosen the ring nut 41, therefore the projection 44 and the openings 29 constitute a nut lock.

5 By providing a nut lock, the threads on the collar 41 and the threads 28 can be made relatively coarse so quick adjustment can be made. If there was no provision made for locking the parts, a finer thread would 10 be necessary and even then there would be no assurance that the parts would become accidentally detached.

15 The pentagonal frame is received in an envelope 45 which constitutes the mop fabric, there being an opening 46 through which the frame may be inserted and the mop fabric can be securely fastened to the frame by the two sets 47 and 48 of string or tapes which may be wound around the cleats 49 20 and 50 on the bars 8 and 9 (see Fig. 1). Since the envelope entirely covers the frame and since the shank and frame are hinged together, it will be apparent that the mop is entirely reversible.

25 I am aware that a reversible mop or brush has been used prior to my invention as for example, the mop disclosed in the patent to W. Q. Glass, December 15, 1914, #1,121,008 and that wire frames for mop heads have 30 also been used prior to my invention. A wire frame is shown in the patent to Toof, patented October 15, 1918, so I do not claim broadly the wire frame nor the reversible mop fabric, but my invention consists rather 35 in the novel manner of forming a rigid frame of a single piece of wire in the form of a flat broad head so that the fabric can have a flat bearing surface on which it operates and a by no means unimportant part of 40 my invention is the novel manner of forming the frame and the manner of securing the shank thereto.

45 The ferrule for connecting the head to the handle or mop stick constitutes the subject matter of a separate application for patent, so no claim for it is made here.

What I claim and desire to secure by Letters-Patent is:

1. A mop head comprising a flat frame of

wire bent intermediate its ends to provide 50 diverging portions, parallel arms integral with the diverging portions, inwardly extending portions at the ends of the parallel arms, inwardly directed diverging arms at the inner ends of the inwardly extending 55 portions and terminating in reversely bent ends to provide clip brackets, the brackets being fast to the parallel arms, a sheet metal clip fastened to the brackets and a shank hinged to the clip.

60 2. A floor-polishing mop head comprising a flat frame formed of wire bent intermediate its ends to provide side bars and end bars, one set of end bars being spaced apart, the spaced ends being bent inwardly to provide diverging arms within the perimeter of the frame, the ends of the arms being bent laterally one toward the other and terminating at the longitudinal center of the frame in reversed bends, doubled upon the 70 lateral portions to provide bracket members, the ends of the wire being secured to the side bars, all parts of the frame being in the same plane, a shank and means for hinging the shank to the bracket members.

65 3. A floor-polishing mop head comprising a flat frame formed of wire having midway of its length two diverging portions, two parallel portions at the ends of the diverging portions, two inwardly extending portions at the ends of the parallel portions, two diverging portions at the ends of the inwardly extending portions, the second mentioned diverging portions being directed toward the first mentioned diverging portions, and two transverse portions at substantially right angles to the second mentioned diverging portions, the transverse portions having reversed bends at substantially the longitudinal center of the frame so that the end portions of the wire are doubled back upon the transverse portions, the ends of the wire being fastened to the parallel portions, and means for fastening a mop handle to the transverse portions.

75 90 95 In testimony whereof I affix my signature.

HERBERT M. STURGIS.
